UNITED STATES PATENT OFFICE

HAROLD I. DANZIGER, OF NEW YORK, N. Y.

ELECTRICAL CONDENSER AND METHOD OF MAKING SAME

Application filed December 26, 1928. Serial No. 328,338.

My present invention relates generally to electrical condensers, and has particular reference to the fixed variety wherein layers of conducting material are arranged in alternate relationship with respect to layers of insulating material.

Before describing the details of my present invention, I will premise that one type of condenser body of the character to which my invention relates is constructed by interwinding, in coiled relationship, strips of conducting material such as foil, and strips of insulating material such as paper, the entire body being subjected to suitable heat and vacuum treatment to expel the air and moisture therefrom, and being thereupon impregnated with a suitable dielectric material, such as wax or oil.

A general object of my invention is to provide a condenser of the foregoing character and a method of manufacturing the same whereby the cost of manufacture is reduced and whereby the efficiency and life of the condenser, and its capability of withstanding the application of relatively high voltages, is increased.

One of the purposes of the paper customarily employed in interposition between the foil layers has been to separate such layers in insulated relationship in a positive manner. The ideal type of condenser, however, would dispense with such paper entirely, for a number of reasons. In the first place, the dielectric qualities of wax or oil, heretofore associated with the paper by impregnation, are superior to the dielectric qualities of the paper itself. In the second place, the employment of paper necessitates very careful preliminary treatment to remove entrained gases and moisture, and even the most painstaking treatment cannot remove every vestige of such substances. In the third place, the nature and constituency of paper renders the same conducive to the gradual development of leakage current paths therethrough. In the fourth place, a breakdown caused by the gradual and continued passage of a leakage current through the paper usually causes the same to char, producing a tear or opening with carbonized edges, the latter projecting

in various directions out of the plane of the paper and facilitating the further passage of leakage currents.

The employment of paper has heretofore been deemed particularly necessary in cases where the impregnating medium is a liquid such as oil, for in such an event the hardening characteristic of wax or the like is absent and there is danger of the foil layers contacting with one another. Oil has a number of advantages over wax as an impregnating medium, among which is the fact that the liquid character of the oil facilitates the dissipation of heat, thereby serving in a measure to prevent the disastrous effects of charring previously referred to.

In my co-pending application Serial No. 215,787, filed August 27, 1927, I disclosed a construction wherein the advantageous qualities of oil had been attained in a highly efficient manner, and wherein the proportion of oil to carrying medium in a comparatively large thickness of insulating layer had been materially increased. More particularly, I disclosed a composite insulating layer, the main portion of which consisted of a relatively bulky and porous material, this material being sandwiched between two relatively dense and thin outer layers of paper or the like.

One of the objects of my present invention is to attain the advantageous results of the construction illustrated and described in said pending application. A more particular object is to attain these results without resorting to the employment of a composite insulating layer of the character therein mentioned.

Briefly, I have provided a condenser where in a relatively porous and highly absorbent material may be satisfactorily employed by itself without sandwiching the same between layers of relatively dense paper or the like. For example, in accordance with my present invention, I may employ material of the relatively coarse and porous character of woven or textile material, such as cheesecloth or the like. In certain cases I have found it satisfactory to employ material which is not necessarily woven, but which has the same

desirable qualities from the standpoint of the contemplated purpose. For example, a relatively thick and coarse unsized paper may be employed, or a paper deliberately provided in 5 advance with a number of openings or apertures.

Thus, although I do not entirely dispense with a positive layer of material for separating the foil layers, nevertheless by my 10 present invention I aim to approach a step nearer to the ideal type of condenser structure. The type of material which I employ may be generically referred to as foraminous in nature.

15 In resorting to a perforated or foraminated material it has been necessary for me to provide means for assuring a continuous separation between the conducting layers. In other words, although a foraminated insulating layer approaches an ideal condition and affords accommodation for a relatively greater percentage of the highly desirable dielectric material such as wax or oil, it also presents the danger previously mentioned of 20 having the conducting layers of foil contact with each other through the perforations or foramina. In accordance with my present invention, I have obviated this difficulty by suitably proportioning the thicknesses and 25 relative bodies of the conducting and insulating layers, as well as by suitably providing for their respective tensions.

30 The manner in which I have attained the foregoing objects and such other objects as 35 may hereinafter appear or be pointed out will be more clearly understood upon reference to the accompanying drawing, in which—

Figure 1 is an enlarged cross-sectional view 40 through a portion of a condenser body constructed in accordance with my present invention and employing a woven material;

Figure 2 is a view similar to Figure 1 illustrating the employment of a pre-perforated material of an unwoven character;

45 Figure 3 is a similar view illustrating the possible employment of a suitable material which is neither deliberately perforated nor woven; and

Figure 4 shows a finished condenser body 50 of the rolled type.

In Figure 1, I have shown a fragmentary cross-section through a condenser body, and have, for the sake of simplicity, illustrated only two adjacent conducting layers 10 and 55 11. These layers may be of suitable foil, such as tin, copper, or aluminum. Interposed between these layers I provide a foraminated material such as a woven textile 12. Ordinary cheesecloth or the like has proved to be 60 satisfactory for this purpose. Of course, it will be understood that a second foraminated layer of the same material on the opposite side of either of the layers 10 and 11 is provided to keep the conducting layers out of contact 65 where the condenser is to be of the rolled type.

The employment of a woven material has several advantages. In the first place, it is an absorbent material, so that the application of an impregnating medium such as oil will result in thorough absorption of the oil 70 by the fibers of the woven material. In the second place, the woven material is by nature provided with openings therethrough, and these openings afford additional space for free unabsorbed impregnating medium. In 75 the third place, the woven material is comparatively thick as compared with the thickness of the paper layer customarily employed. Inasmuch as the breakdown voltage of a condenser is dependent upon the space between 80 the conducting layers, a relatively great thickness of the woven material provides for a high breakdown voltage.

If the woven material is sufficiently thick and the spaces between the strands are sufficiently small, I have found that there is no danger of contact between the separated foil layers. Where the material is very loosely woven, so that the ratio of space between 85 strands to thickness of material is increased, I assuredly prevent short-circuiting by increasing the tensions of the foil layers during the association thereof with the insulating layer. This tension may, for example, be maintained during manufacture by suitably 90 braking the reels from which the strip material is fed to the winding mandrel or the like, and the usual sticker 20 (Figure 4) which is applied to the wound body 21 after 95 the winding procedure is completed serves to maintain the proper conditions in the finished condenser body.

In accordance with my invention, I employ a woven material which is as loosely woven as possible so that most of the space between the foil layers is occupied by the dielectric material, such as oil. In this way, I approach the ideal construction wherein such space is occupied entirely by the dielectric material.

In Figure 2 I have shown the possible employment between foil layers 13 and 14 of an unwoven material 15 purposely provided in advance with a series of perforations or 105 foramina 16. For example, a material such as coarse unsized and relatively thick paper has proven satisfactory, and its characteristics are very similar to the characteristics previously mentioned in connection with the 110 woven material 12. The coarse nature of the paper renders it highly absorbent so that it may accommodate a very large amount of the impregnating medium such as oil. The thickness of the paper provides for a maximum distance between foil layers, thereby increasing the breakdown voltage. The openings 16 afford accommodation for free oil, where the latter is the medium employed, and these openings are made as large as possible 115 with relationship to the maximum permissi- 120 125 130

ble tension that may be applied to the foil layers 13 and 14.

Instead of tensioning the foil layers, I have found it satisfactory to increase their 5 thicknesses, thereby imparting greater body to them and consequent greater resistance to buckling.

In Figure 3 I have shown the possible employment between foil layers 17 and 18 of a 10 relatively thick layer 19 of coarse unsized paper which has not been previously perforated. The employment of such unperforated paper is capable in a measure of fulfilling the general aim of the present invention, 15 provided that the texture of the paper is sufficiently coarse so that it may be reasonably termed a "foraminous" layer.

Obviously, where perforations are absent, as in Figure 3, the thickness and tension of 20 each foil layer may be correspondingly reduced.

It will thus be seen that I have provided a condenser and a method of constructing the same whereby the cost of manufacture is materially reduced, and whereby the advantageous qualities of oil may be efficiently resorted to. To demonstrate by means of figures the advantageous results achieved by my present invention, I will point out that a theoretical condenser having nothing but oil between its foil layers might be assumed to have a breakdown voltage of approximately thirty thousand volts. Where paper is employed in the customary and well known manner, the breakdown voltage may be in the neighborhood of forty thousand volts, but it would be unsafe to operate the condenser under a continuing voltage greater than twenty thousand volts. Thus, during a 25 twenty thousand volts' safe operation, the life of the condenser might be approximately ten years. In the theoretical condenser, however, the life of the condenser would be practically unlimited even during a continuous 30 operation under as much as twenty-five thousand volts. The reason for this lies in the fact that a breakdown in the theoretical condenser would be caused only by oxidation of the oil, whereas a breakdown where paper 35 is employed would be caused most probably by a breaking or tearing of the paper due to leakage currents.

It is obvious that the employment of a foraminous material, such as cheesecloth, pre- 40 perforated highly absorbent paper or the like, approaches a condition equivalent to the theoretical condenser; and I have, as a matter of fact, found by tests that the condensers constructed in accordance with the present 45 invention may be continuously employed under greater voltages and for longer periods of time than has been possible heretofore.

It will also be understood that although I 50 have herein illustrated the invention as it is 55 applied to a condenser of the rolled type,

nevertheless the invention is not necessarily restricted to this particular type of condenser, and may be applied with almost equal facility to condensers of the stacked type, in which case suitable clamping devices engaging either the edges of the foil strips or other portions of such strips would serve to hold the strips in sufficient tension to prevent any buckling of the strips through the spacing layers. 75

The details herein described and illustrated are intended to serve in explanation of the nature of my invention and are therefore to be interpreted as illustrative and not in a limiting sense, unless the prior art should require such limited interpretation. 80

Having thus described my invention and illustrated its use, what I claim as new and desire to secure by Letters Patent is—

1. An electrical condenser comprising a set 85 of alternately arranged conducting and foraminated insulating layers, the latter being in direct contacting sandwiched relationship to the conducting layers, and the conducting layers being sufficiently tensioned to prevent 90 buckling thereof.

2. In an electrical condenser, the combination of a pair of foil conducting layers and a loosely woven insulating layer sandwiched therebetween in direct contact with said foil layers, the latter being sufficiently tensioned to prevent buckling thereof through the foramina of the woven layer, said combination of layers being impregnated with a liquid dielectric material which fills in the interstices 100 and foramina of the woven layer. 95

3. An electrical condenser body comprising a set of spirally interwound, alternately arranged, metallic foil conducting strips and insulating strips, the insulating strips comprising relatively thick and highly absorbent unsized paper having perforations therethrough, and the foil strips being sufficiently tensioned to prevent buckling thereof 105 through the perforations of the insulating strips. 110

In witness whereof, I have signed this specification this 10th day of December, 1928.

HAROLD I. DANZIGER.
